COMBINED BATHTUB SPOUT, HAND GRIP, SOAP HOLDER AND CONTROL KNOB

Paul A. Mongerson, Elyria, Ohio, assignor to Standard
Screw Company, Hartford, Conn., a corporation of New
Jersey

Filed Nov. 14, 1967, Ser. No. 9,550

Term of patent 14 years

(Cl. D23—32)

FIG. 3.

FIG. 4.

FIGURE 1 is a front elevational view of a combined bathtub spout, hand grip, soap holder and control knob showing my new design;

FIGURE 2 is a side elevational view, with portions broken away to illustrate detail configuration thereof;

FIGURE 3 is a top plan view thereof; and

FIGURE 4 is a bottom plan view thereof.

I claim:

The ornamental design for a combined bathtub spout, hand grip, soap holder and control knob, as shown.
